UNITED STATES PATENT OFFICE.

THOMAS BRABSON, OF NEWARK, NEW JERSEY.

BRIDLE-BIT.

SPECIFICATION forming part of Letters Patent No. 394,454, dated December 11, 1888.

Application filed October 8, 1888. Serial No. 287,507. (No model.)

To all whom it may concern:

Be it known that I, THOMAS BRABSON, a citizen of the United States, residing at Newark, in the county of Essex and State of New Jersey, have invented new and useful Improvements in Flexible Mouth-Pieces for Bridle-Bits, of which the following is a specification.

This invention relates to bridle-bits having flexible mouth-pieces; and it consists in a novel construction of a bridle-bit provided with a flexible mouth-piece, as is fully described and claimed in the following specification, reference being had to the accompanying drawings, in which—

Figure 1 is a front elevation of a bridle-bit containing my invention, the flexible mouth-piece being for the most part in longitudinal central section. Fig. 2 is a similar elevation, in which the covering of the mouth-piece is in longitudinal section. The figure also shows in partial section the connection of one end of the flexible mouth-piece with the bit-ring.

Similar letters indicate corresponding parts. The letter A designates a bridle-bit which is provided with a flexible mouth-piece, B, whose ends are connected, as hereinafter described, to the bit-rings C C.

The flexible mouth-piece B consists of a central flexible core composed of a series of links, D, connected to each other at their ends and constructed by forming a chain of wire links, e e e, as many in number as are required for the length of the chain, and then casting upon the central part of each link e a block, f, in such a manner that the blocks f cannot slide on the links. The end links, e e, are interlocked with links g g, which connect the combined links and blocks e f with the bit-rings C. The connecting-links g are connected to the bit-rings in such a manner that the bit-rings and the links can freely turn on each other. Two methods of accomplishing this are shown.

In Fig. 1 the links g g are bored out and provided in their outer ends with internal screw-threads, h, into which are screwed the threaded ends i of eyebolts J, which are secured between the jaws k k of the bit-rings in the usual manner.

In Fig. 2 the outer ends of the connecting-

links g g are inserted between the jaws k k of the bit-rings, and are secured by a bolt, L, which passes through the jaws k k and the link g and is fastened in that position, so that the bit-rings and links can freely turn on each other.

Before the links g g are secured to the bit-rings the flexible core D is surrounded with a covering of india-rubber, M, which may be in the form of a tube of proper size to fit closely upon the core D. The ends of the rubber covering are fitted closely over the ends of the core D, where they meet the bit-rings, so as to make a tight joint there against the entrance of moisture into the rubber and the core D, and in the example shown in Fig. 1 the inner ends of the eyebolts J are recessed at n n to admit the ends of the rubber covering within the recess and thus obtain a tight joint.

The blocks f and links g are in this example cast from iron and are of the same diameter, substantially, so as to make the rubber covering smooth and the mouth-piece of uniform size.

By casting the blocks f upon the wire links e the links e are protected, except the end-protruding portions, from injury by moisture, which might gain entrance under the rubber covering M.

What I claim as new, and desire to secure by Letters Patent, is—

1. The combination, with the bit-rings of a bridle-bit, of a mouth-piece comprising end links, g, a series of intermediate connected wire links, e, and a block, f, cast upon and around each one of said intermediate links and constituting an immovable part thereof, substantially as described.

2. The combination, with the bit-rings of a bridle-bit, of end links, g, blocks f, and a series of wire links, e, passing centrally through, rigidly fixed in, and projecting beyond the axis of the blocks, substantially as described.

In testimony whereof I have hereunto set my hand and seal in the presence of two subscribing witnesses.

THOMAS BRABSON. [L. s.]
